UNITED STATES PATENT OFFICE.

ALVIS M. RAY, OF TACOMA, WASHINGTON.

DISPLAY-CARD HOLDER.

Application filed December 29, 1927. Serial No. 243,397.

This invention relates to display card holders and more particularly holders of this class which are designed to be secured to a suitable support such, for example, as the filling neck of an automobile radiator. Such display cards are usually printed upon cardboard and are liable to be torn from the support, and the object of the present invention is to provide a cheap card holder of this class which will securely clamp and hold a pasteboard card, and which may be readily secured to a support such as the filling neck of an automobile radiator.

With this object in view the invention consists, generally stated, of an integral piece of metal, either in the form of a strip of sheet metal or of a wire, so bent as to form two parallel card-clamping portions, and a shank extending at right angles therefrom and terminating in an adjustable loop, together with means for clamping the card between said parallel clamping portions and clamping the loop to the support.

The invention further resides in a blank for making such a display card holder, which blank consists of a strip of sheet metal with a series of holes or perforations at one end thereof, a hole or perforation at the other end thereof, and perforations in the body of the blank so positioned that when the blank is bent to form the holder, the several perforations will register so as to enable the clamps to be inserted therethrough and through the card for clamping the card and to tighten the loop around its support.

The invention is illustrated in the accompanying drawing in which

Figure 1 is a perspective view of the invention shown attached to the filling neck of an automobile radiator;

Figure 2 is a plan view of the form of the invention shown in Figure 1;

Figure 3 is a plan view of the blank from which the holder of Figures 1 and 2 is made; and

Figure 4 is a plan view of a holder embodying the invention, the same being made of a single piece of wire bent into proper form to provide the clamping surfaces, the eyelets through which the clamps are passed, and the shank and loop as in the other form.

Referring to the drawings, in which like reference characters indicate like parts throughout the several views, and first to Fig. 3, 1 indicates a blank of sheet metal provided at one end with a series of holes 2, and at the

other end with a single hole 3. Adjacent to the holes 2 but sufficiently removed therefrom to afford metal for forming a loop is a hole 4. In the body of the blank are two pairs of holes, 5, 5' and 6, 6'. Preferably the holes of these two pairs are of oblong shape in order to facilitate the ready register of the parts with respect of each other when the blank is bent into the form of a card holder, as hereinafter described.

This blank constitutes in and of itself an article of manufacture which may be readily and compactly shipped to the consumer, and may be readily bended into the display card holder now to be described.

Referring to Figs. 1 and 2, a strip of sheet metal is bent at the points 7 and 8 sharply upon itself so that the end portions 9 and 10 lie parallel with and closely adjacent to the middle portion 11. The end portion 9 at approximately the medial point of the portion 11, has its terminal part 12 bent at right angles to the middle portion 11. The end portion 10 has its terminal part 13 bent at right angles to the middle portion at approximately the medial point of the latter and parallel with the terminal part 12 of the end portion 9, and then into the form of a loop 14, and finally has its extreme end portion 15 extended back toward the middle portion 11 parallel with the terminal part 12 of the end portion 9, said terminal part 12 being embraced or held between the terminal part 15 and the shank portion of the terminal part 13. In this position one of the holes 2, see Fig. 3, the hole 3, and the hole 4 will register, and a clamp screw 16, provided with a wing nut 17, is passed therethrough, and by this means the loop tightened to firmly engage the support. The series of holes 2 in the blank 1 affords means whereby the size of the loop may be adjusted within limits to properly fit the support.

With the parts bent as indicated above, the two holes 5 and 5' will register with each other and a clamp screw 18 is passed therethrough, and the two holes 6, 6' may also be brought in register to the end that the clamp screw 19 may be passed therethrough. A card 20 is inserted between the portion 11 and the portions 9 and 10 with the clamp screws 18 and 19 passing through the card. By this means the card is not only supported by means of the clamp screws which pass through openings in the card, but it is also firmly clamped between the opposing faces of

the support, and this prevents the card being torn from its position, unless by the application of very considerable force.

Referring now to Fig. 4, 21 is a wire bent sharply at the points 22 and 23 so as to bring the end portions 24 and 25 parallel with the middle portion. The terminal part 26 of the end portion 24 is first bent at right angles to the middle portion to form a shank, then into a clamp screw receiving loop 27, after which it is bent into a support engaging loop 28, and finally into a hook-shaped part 29. The other end portion 25 has its terminal end portion 30 bent at right angles to the main clamping body of the holder and parallel to the shank portion 26 of the member 24, and at the extreme end is turned to form a loop or eye 31. A clamp screw 32, having an eye 33 passed over the hook 29, is then passed through the loops 31 and 27 and has a wing nut 34 thereon for tightening the loop 28 around the card holder support.

The parallel clamping members constituting the parts for clamping the card are then bent on themselves so as to form loops or eyes 35, 36, and clamping screws 37 and 38 are passed through said loops or eyes and through the card between the clamping members, and wing nuts 39 and 40 are applied thereto to securely clamp the parts and the card in secure position.

It will be perceived that by the present invention there is provided, first, a blank which may be shipped in large numbers in very compact space; second, there is provided a card holder that can be made at a minimum cost, which will securely clamp a pasteboard card and insure the same from being readily torn from its support, and which may be readily and securely clamped to a support such as the filling neck of an automobile radiator.

What is claimed is:

1. A display card holder consisting of an integral piece of metal bent to form two

parallel oppositely disposed card clamping portions, a loop intermediate the extremities of said card clamping portions at right angles thereto and a shank connecting said loop and card clamping portions, clamping members on opposite sides of said shank and clamping said card clamping portions, and a clamp on said shank for tightening said loop. 45

2. A display card holder consisting of a strip of metal having each end portion bent on the middle portion and parallel therewith to approximately the medial point of said middle portion, at which point the terminal part of one end portion is bent at a right angle into a shank portion and the terminal part of the other end portion is bent at a right angle first into a shank portion, then a loop portion, and then a second shank portion, all of said shank portions being parallel and having a clamp member passing therethrough, and two clamp members, one on either side of said shank and clamping said middle portion to the parts parallel therewith. 55

3. A blank for forming a display card holder, said blank consisting of a strip of sheet metal having a series of closely spaced holes at one end, and a single hole adjacent but somewhat removed from said series of holes, and a hole near the other end of said strip, said strip further having two pairs of spaced holes in its body portion, whereby said strip may be bent on itself between the holes of each of said pairs of holes to bring the holes of each pair into register, and the end having the series of closely spaced holes may be bent into a shank and a loop with one of the said series of holes in register with said hole adjacent thereto and also in register with the hole in the other end, when said last named end is bent parallel with the end having the series of holes. 60

In testimony whereof I have signed this specification.

ALVIS M. RAY.
